UNITED STATES PATENT OFFICE.

CHARLOTTE V. GULICK, OF NEW YORK, N. Y., ASSIGNOR TO CAMP FIRE OUTFITTING CO., OF NEW YORK, N. Y., A CORPORATION OF NEW YORK.

DESIGN FOR A FRAME FOR BEADWORK-LOOMS.

46,497.

Specification for Design.

Patented Oct. 6, 1914.

Application filed July 8, 1914. Serial No. 849,857. Term of patent 14 years.

To all whom it may concern:

Be it known that I, CHARLOTTE V. GULICK, a citizen of the United States, residing at New York city, in the county of New York and State of New York, have invented a new, original, and ornamental Design for Frames for Beadwork-Looms, of which the following is a specification, reference being had to the accompanying drawing, forming part hereof.

Figure 1 is a plan view of a frame for a

bead work loom, showing my new design; Fig. 2 is a side elevation of the same; and Fig. 3 is an end elevation of the same.

I claim:

The ornamental design for a frame for a bead work loom, as shown.

CHARLOTTE V. GULICK.
